CLAIM

The ornamental design for a cartridge, as shown and described.

DESCRIPTION

FIG. 1 is a perspective view of the cartridge showing of our new and ornamental design;

FIG. 2 is an alternate perspective view thereof;

FIG. 3 is top view thereof;

FIG. 4 is a bottom view thereof;

FIG. 5 is a side view thereof;

FIG. 6 is an opposite side view thereof;

FIG. 7 is a front view thereof; and,

FIG. 8 is a rear view thereof.

The portions of the cartridge shown in broken lines shown in the figures attached hereto form no part of the claimed

(Continued)

design. The unshaded surfaces immediately adjacent to the broken lines depict portions of the cartridge that form no part of the claimed design.

1 Claim, 8 Drawing Sheets

Related U.S. Application Data

continuation of application No. 29/591,550, filed on Jan. 20, 2017, now Pat. No. Des. 852,975, which is a continuation-in-part of application No. 29/571,987, filed on Jul. 22, 2016, now Pat. No. Des. 836,793.
